UNITED STATES PATENT OFFICE.

LUTHER F. COSBY, OF DALLAS, TEXAS.

AUTO STEERING-LOCK.

1,342,276.

Specification of Letters Patent. Patented June 1, 1920.

Application filed October 23, 1918. Serial No. 259,348.

To all whom it may concern:

Be it known that I, LUTHER F. COSBY, a citizen of the United States, residing at Dallas, in the county of Dallas and State 5 of Texas, have invented new and useful Improvements in Auto Steering-Locks, of which the following is a specification.

This invention comprehends generally improvements in that class of inventions 10 known as locks and latches, and more particularly has reference to an auto steering lock.

It is the principal aim and object of the present invention to provide a device of the 15 above mentioned character wherein coöperative means are mounted on the steering post and steering wheel and designed to be arranged in engagement with each other to prevent turning of the steering wheel, thus 20 preventing unauthorized persons from appropriating the machine.

More particularly the present invention consists in the provision of a device of the above mentioned character wherein a cross 25 bar is mounted on the steering post and is designed to be engaged by the shanks of the locking members which detachably engage the spokes of the steering wheel, while a padlock is employed in conjunction with 30 the locking members for holding them together and in close relation with the cross arm so as to prevent turning of the wheel relative to the post.

It is a more specific object of this invention 35 to provide a device of the above mentioned character wherein the locking members are of improved construction capable of being easily and quickly attached to the spokes of the wheel and removed therefrom 40 when desired.

Among the other aims and objects of this invention may be recited the provision of a 45 device of the character described with a view to compactness, and in which the number of parts are few, the construction simple and the cost of production low and the efficiency high.

Other improvements and novel details in the construction and arrangement of the 50 various parts of the apparatus will be brought out more in detail in the description to follow, which for a clear understanding of the invention should be considered in connection with the accompanying drawings 55 forming a part hereof, and wherein is disclosed for the purpose of illustration a con-

venient and satisfactory embodiment of the invention. It is to be noted in this connection that minor changes in the construction and arrangement of parts may be made 60 without departing from the principle of operation of the various parts.

The invention is clearly illustrated in the accompanying drawings, in which—

Figure 1 is a front elevation of the invention 65 attached.

Fig. 2 is a rear elevation thereof.

Fig. 3 is a perspective detail of one of the locking members.

Fig. 4 is a cross section taken on line 4—4 70 of Fig. 2.

Similar characters of reference are employed in all of the above described views, to indicate corresponding parts.

Referring now, more particularly, to the 75 accompanying drawings there is provided a steering post 1 in which is mounted a steering rod 2 on the upper end of which is carried a steering wheel 3 embodying a hub 4 from which radiates spokes 5 connected at 80 their outer ends to the rim 6. In this connection it is to be noted that the spokes diverge from the hub to the rim as is the case in the conventional construction of wheels. Operably connected to the post and wheel is 85 the improved lock indicated in its entirety by the numeral 7, designed for preventing movement of the wheel relative to the post.

In reducing the present lock to actual practice there is employed a cross bar 8 90 which is formed with curved terminals 9 and with an arcuate intermediate portion 10 to incidentally provide a clamp section, while coöperating therewith is another clamp section 11 which is arcuate in cross section and 95 terminates in securing portions 12 which are arranged in abutting relation at one face of the cross bar and secured thereto by suitable nut and bolt arrangements 13 for the clamping of the arcuate portions of the 100 sections 10 and 11 in opposed relation to each other and about the upper end of the steering post or column 1, as indicated in the drawings.

Coöperating with the curved end portions of the cross bar 8 are the complementary locking members, each indicated in its entirety by the numeral 14. In each instance each locking member consists of a shank 15 formed at its upper end with a 110 right angularly projecting hook 16, the bill 17 of which is curved downwardly and in-

wardly and terminates in spaced relation to the shank to permit of the arranging of these hook members over the restricted ends of opposed spokes and the sliding of the 5 hooks toward the hub, and a consequent frictional engagement of the hooks with the large inner portions of the opposed spokes. This arrangement serving as a means for 10 securely, yet removably connecting the locking members to the spokes. Formed at the lower ends of the shanks are inwardly extending curved arms 18 which terminate in outwardly extending flanges or ears 19 having 15 openings therein. When the hooks are engaged in the manner described, the shanks 15 bear against the curved portions, while the curved arms 18 are arranged to embrace the post 1, as indicated and are removably held in this position through the medium of 20 a padlock 20, the shackle 21 of which is designed to be passed through the openings in the openings of the ears or flanges 19, as indicated and thus serves as a means for 25 rigidly holding the parts in abutting relation with each other to consequently prevent independent turning of the wheel relative to the post 1 and as a result prevents thefts of the machine to which the device 30 is attached.

30 It is thought in view of the foregoing description that a further detailed description of the operation of the invention is entirely unnecessary. Likewise it is believed that the advantages of the invention will be 35 readily apparent.

As many changes could be made in the above construction and many apparently 40 widely different embodiments of this invention could be made without departing from the scope thereof it is intended that all matter contained in the above description or shown in the accompanying drawings shall be interpreted as illustrative and not in a limited sense. It is also to be understood 45 that the language used in the following claims is intended to cover all the generic and specific features of the invention herein described and all statements of the scope of the invention which as a matter of 50 language might be said to fall therebetween.

What is claimed is:—

1. The combination with a steering post and a steering wheel, of a motor vehicle, of

a cross bar rigidly clamped to the post, locking members formed at the upper ends 55 with hooks for embracing the spokes of the wheel and at their lower ends with arms for embracing the post, and locking means for holding the arms and hooks in position and for holding the members against the cross bar.

2. The combination with a steering post and a steering wheel, of a motor vehicle, of a cross bar, means for clamping the bar to the post so that the respective ends will project beyond the sides of the post, complementary locking members formed at their upper ends with hooks for embracing the spokes of the wheel and formed at their lower ends with arms for embracing the post in such a manner that the members will abut the projecting ends of the cross bar, and a padlock engageable with the arms for holding the members against movement to consequently prevent movement of the wheel relative to the post.

3. The combination with a steering post and a steering wheel, of a motor vehicle, of a cross bar having curved terminals and forming a clamp section for embracing a portion of the post, another clamp section secured to the cross bar and embracing the opposite side of the post for cooperating with the bar in insuring of the maintenance of the bar in a rigid position on the post, 80 a pair of complementary locking members each consisting of a shank, a hook projecting at right angles from the upper end of the shank and having a curved bill terminating in spaced relation to the shank for 85 disposition over the restricted outer portion of one of the spokes of the wheel and for frictionally engaging the inner portion of the said spoke, the locking members being positioned on opposed spokes so that the shanks abut the cross bar, a curved arm projecting from the lower end of the shank and formed with an ear terminal, the arms of the locking members embracing the post, and a padlock having its shackle engaged 100 in the ear terminals of the locking members for preventing relative movement of the parts.

In testimony whereof I affix my signature.

LUTHER F. COSBY.
